UNITED STATES PATENT OFFICE

1,940,247

MEANS FOR REFORMATION OF METAL WHEELS

Ashby P. Conner and Ralph L. Jasperson, South Bend, Ind.; St. Joseph Loan and Trust Co. administrator of said Ashby P. Conner, deceased

Application November 19, 1931
Serial No. 576,196

5 Claims. (Cl. 153—32)

The invention relates to forms for use in straightening or restoring to normal condition metal wheels that have become bent or otherwise distorted; and, in particular, it provides strong 5 metal forms of a size, shape, and contour conforming to the shape of the rims and hub structure of wire-spoked wheels and adapted to insure that the wheel structure is restored to proper shape and form during the application of heat, 10 hammering, and/or pressure thereto.

When considered with the description herein, the characteristics of the invention are apparent from the accompanying drawings, constituting part hereof, wherein are shown forms of the 15 types provided by the invention.

Like reference-characters refer to corresponding parts in the views of the drawings, of which—

Fig. 1 is an elevation of a machine of a type 20 in which the forms may be used;

Fig. 2 is a plan view of a rim-form;

Fig. 3 is a section on the line 3—3, Fig. 2;

Fig. 4 is a plan view of a hub-form;

Fig. 5 is a section on the line 5—5, Fig. 4;

Fig. 6 is an elevation of rim and hub forms in 25 cooperative assembly;

The invention provides annular trued rim-forms 9, shaped in plan to conform approximately to the normal configuration of the sides 30 of the rims of the types to be used upon them.

One example of such forms, adapted to be used in straightening laterally or axially distorted wheels of one of the commercial types, is illustrated, more particularly, by Figs. 2 and 3. The 35 form thus shown is a ring having a comparatively large central opening therethrough, provided so that a wheel hub and spokes may extend freely thereinto and the rim permitted to rest on the ring unretarded by the hub and spokes.

40 when one side of the wheel is placed against the form. The ring has a flat lower surface, whereby the form is adapted to lie flat upon the bed of a press, upon a bench, or upon any other suitable base; it has outwardly-extending lugs 45 10 to take any suitable fastenings for holding it in place; and it has an upwardly-extending continuous outer flange 11, an upwardly-extending continuous inner flange 12 of less height, and between the flanges a continuous groove 13.

50 The forms are made of strong metal of a kind that will withstand relatively high heat, and also pressure and hammering, without distortion, it being essential that the forms at all times retain the shape required for the rims to be treated

thereon.

When a form is used, the rim of a wheel is laid side down on the form of the particular size and shape to accommodate that type of wheel. When necessary to effect restoration to normal shape, the rim may be heated, either before or after it is laid on the form, by any suitable means. While the wheel is lying with its rim on a form, or while a separate rim is lying thereon, the rim may be straightened by hammering, or by the application of pressure thereto 60 in a press or by any other suitable means.

The invention also provides strong undistortion metal hub-forms 14, as exemplified by Figs. 4, 5, and 6, adapted to be placed centrally on rim-forms, the hub-forms having outer 70 flanges 15 adapted to rest on the inner flange of a rim-form and an annular abutment 16 arranged to fit closely into the inner periphery of the rim-forms with which it is intended to be used.

When the wire spokes of a wheel and/or its hub have been distorted, when spokes have become disconnected (as, for example, the spokes A at the hub as shown in Fig. 1), or when, for any other reason, it is desirable to hold a wheel 80 down at the hub and against a rim-form, a hub-form, of the appropriate size and shape, is laid on a rim-form, also of the appropriate size and shape, the rim is laid on the rim-form, and pressure is applied, by a press or other suitable means, to the hub-cage to bring it down against the hub-form. The spoke-and-hub structure of the wheel thus is restored to normal condition or place.

While the spoke-and-hub structure is under 90 pressure, and the wheel in its entirety thus is in place in normal form, bent spokes may be straightened, spokes disconnected at either or both ends may be rewelded or riveted to the hub and/or rim, and spokes that have been lost 95 or removed as unsuitable for repair may be replaced by new ones.

The rim-forms may be made, in accordance with the invention, in sets of the proper sizes and shapes to accommodate metal-rim wheels of 100 the several types and dimensions in general use on vehicles. Similarly, the hub-forms may be made in sets of the sizes and shapes corresponding to a number of the types of wheels and of the sizes to enable them to seat on the rim-form 105 corresponding to the entire structure of the wheel to be treated. Moreover, the hub-forms are of such vertical dimensions that, when the proper one for the wheel to be treated is in place on a rim-form, the hub-and-spoke structure will 110

be in normal place when pressed down against the hub-form.

Fig. 1 illustrates a stand B of a type suitable for use in employment of rim and hub forms 5 of the character provided by the invention, a rim-form being shown as resting on top of the stand, a wheel resting on the form, and a screw pressing down against the hub-cage. It is to be understood, however, that Fig. 1 is but illustrative, and that the forms, as hereinbefore explained, may be used advantageously on the bed 10 of a press, on a bench, or on any other base suitable as a support during hammering, pressing, or other treatment of a wheel.

15 What we claim as new, and desire to secure by Letters Patent, is—

1. A set of metal forms for use in reforming metal wheels, said set including a rim-form arranged to have the side of the rim of a wheel to be treated rest thereon, and a removable hub-form arranged to rest on the rim form and to stop at normal position the hub of a distorted hub-and-spoke structure pressed thereagainst.

2. A metal form, for use in reforming metal wheels, comprising an annular member arranged to have a wheel-rim rest sidewise thereon, and a removable central member arranged to stop at normal position the hub of a distorted hub-and-spoke structure pressed thereagainst.

3. A set of metal forms, for use in reforming metal wheels, comprising a ring arranged to have a wheel-rim rest sidewise thereon, and a separate hub-form having an outwardly-extend-

ing flange arranged to rest on top of said ring and an abutment arranged to fit closely into the inner periphery of the ring whereby to center the two said parts, the hub-form being arranged to stop at normal position the hub of a distorted hub-and-spoke structure when its rim rests on said ring and pressure is applied to the hub.

4. A form for reformation of metal wheels consisting of an integral metal ring capable of itself withstanding hammering and pressure without distortion and of lying flat upon a base, said ring being shaped on its upper side to conform to the normal configuration of the side of the rim of a wheel to be laid thereon, and said ring having a comparatively large central opening therethrough capable of accommodating an offset hub of the wheel.

5. A form for reformation of metal wheels consisting of an integral metal ring capable of itself withstanding hammering and pressure without distortion and of lying flat upon a base, said ring having on its upper side an upwardly-extending continuous outer flange, an upwardly-extending inner flange of less height, and between said flanges a continuous annular groove arranged to have the side of a wheel-rim rest therein, and said ring having also a comparatively large central opening therethrough capable of accommodating an offset hub of the wheel.
